UNITED STATES PATENT OFFICE.

ADOLPH LANG AND HARPER F. SMITH, OF PHILADELPHIA, PENNSYLVANIA, ASSIGNORS OF ONE-THIRD TO CHARLES H. ZINK, OF PHILADELPHIA, PENNSYLVANIA.

LAMP.

No. 833,468.

Specification of Letters Patent.

Patented Oct. 16, 1906.

Application filed October 10, 1905. Serial No. 282,118.

To all whom it may concern:

Be it known that we, ADOLPH LANG and HARPER F. SMITH, citizens of the United States, residing in the city and county of Philadelphia, State of Pennsylvania, have invented a new and useful Lamp, of which the following is a specification.

Our invention consists of a novel construction of a lighting device in which both the air and the gas are separately heated before entering the chamber in which they unite. The oxygen in the heated air unites with the heated gas to form a gas and the combination and cohesion between these two heated gases form a distinct and separate gas, which produces an intense heat, and when this heat comes in contact with an incandescent body, such as the mantle of a lamp, a very strong and brilliant light is produced. The volume of air traversing the heated air-chamber will preferably be greater in proportion than the volume of gas passing through the heated gas-chamber, and as the heated air leaves the air-outlet it predominates to such an extent that the gas coming from the heated chamber is carried with it into a second chamber, at which place the affinity between the two gases causes a separate and distinct gas to be produced.

Our invention further consists of a novel and simplified construction of heating-chambers in which one or more tubes are employed, said tubes being connected and arranged in any suitable manner, either vertically, horizontally, spirally, or otherwise, it being only essential that the air and the gas be separately heated.

It further consists in a novel construction of a lamp, in which the heat from the lamp is utilized to heat the separate coils or tubes through which the air and gas, respectively, are conducted.

It further consists of a novel construction of a chamber in which the gas is formed and through which it passes to the burner-tip.

It further consists of other novel features of construction, all as will be hereinafter fully set forth.

Figure 1 represents a sectional view of a lamp embodying our invention. Fig. 2 represents a sectional view similar to Fig. 1, but showing the air and gas tubes as being horizontal instead of vertical and also an air-

compressing device which may be employed, if desired.

Similar numerals of reference indicate corresponding parts in both figures.

Referring to the drawings, 1 designates a pipe, which is in suitable connection with the gas-supply and provided with a controlling-valve 2, which may be of any desired form or of any conventional type adapted to control the flow of the gas.

3 designates a pipe or tube which is suitably connected with the controlling-valve 2 and at its outer end with a cap 4. This cap 4 has a passage 5 therethrough, through which the gas may pass into the pipe or conduit 6, which in the present instance has brazed engagement with the cap 4 at one end and at its other end is secured to a block 7, which is provided with a passage 8.

9 designates a pipe secured to the block 7 and in communication with the passage 8, the other end of said pipe being secured to the cap 4 and having communication with a passage 10 therein.

11 designates a third pipe secured to the cap 4 and in communication with the chamber 10, the other end of said pipe 11 being secured to the block 7 and in communication with a passage 12 therein, which leads to the gas-outlet 13.

14 designates an air-inlet pipe, which is connected with the atmosphere or with any desired type of air-compressor and which is provided with a controlling-valve comprising a valve-casing 15 and a valve 16 having threaded engagement therewith.

17 designates a pipe suitably connected with the valve-casing 15 and also with the cap 4 and through which the air is led to the passage or chamber 18 in the cap 4.

19 designates a pipe connected with the cap 4 and in communication with the passage 18, the other end of said pipe being secured to the block 7 and communicating with the passage 20.

21 designates a pipe secured at one end to the block 7 and communicating with the passage 20 and secured at its other end to the block 4 and communicating with the passage 22 in the cap 4.

23 designates a pipe one end of which is secured to the cap 4 and communicating with the passage 22, the other end of said pipe be-

ing secured to the block 7 and in communication with the passage 24, which leads to the air outlet or nozzle 25, which, as seen in the present instance, is beyond the gas-outlet 13.

5 The gas passing through the outlet 13 and into the space 26, surrounding the air-outlet 25, is drawn or forced by the air passing through said outlet 25 into the chamber 27. The combination between the heated gas and 10 the heated air forms a distinct gas, which is a gas having a high percentage of oxygen, since the oxygen in the heated air combines with the heated gas and oxidizes the same. This gas passes through the chamber 27 into the 15 chamber 28, which forms a continuation of the chamber 27 in the casing 29, which is suitably secured to the chamber 27. The casing 29 is provided in the present instance with two burner-tips 30, although it is evident that the number of burner-tips employed may be varied according to requirements.

20 31 designates a lug extending outwardly from the casing 29 and having secured thereto, by means of set-screws 32, mantle-supporting rods 33, which are bent at the outer end in the form of a hook 34, on which the mantle 35 is supported.

30 36 designates a lug or projection extending from the casing 29, on which is adjustably mounted, by means of set-screws or equivalent devices 37, a bracket 38, adapted to support the globe 39.

35 40 designates a top casing or upper dome, which is adjustably mounted on the tube 3 by means of the set-screw 41.

40 42 designates an outer casing surrounding the air and gas conduits, said casing being secured to the block 7 by means of set-screws 43.

44 designates a reflector, which is fastened to the casing 42 in any suitable manner.

In the embodiment shown in Fig. 2 we have shown the air and gas tubes as extending horizontally instead of vertically, it being apparent that these tubes may be arranged either horizontally, perpendicularly, or otherwise, with respect to the heating device and that the operation will be the same 45 as in the construction shown in Fig. 1. We have, however, shown means for producing an air-pressure, and in this embodiment 45 designates a gas-inlet pipe having a suitable controlling-valve 46, said pipe 45 being connected with a block 47, provided with a chamber 48, having communication with said pipe 45 and also with a pipe 49, one end of which is secured in the block 47, the other end thereof being secured to a block 50, having a chamber or passage 51 therein.

52 designates a pipe secured to the block 50 and in communication with the passage 51, the other end of the pipe being secured to the block 47 and communicating with a passage or chamber 53 therein, said chamber be-

ing also in communication with a pipe 54, secured to the block, the other end of this pipe 54 being secured to the block 50 and communicating with a chamber 55 therein.

56 designates a pipe one end of which is secured in the block 50 and in communication with the chamber 55, the other end thereof being secured to the block 47 and in communication with the chamber 57, which leads to the gas-outlet 58.

59 designates a water or other motor adapted to actuate the bellows 60, whereby the air is compressed and forced through the pipe 61 into the pipe 62, provided with a controlling-valve casing 63, having a valve 16 80 therein, the end of said pipe 62 being secured to the block 47 and communicating with the chamber 63 in said block.

64 designates a pipe secured to the block 47 and communicating with the chamber 63, 85 the other end thereof being secured to the block 65 and communicating with the chamber 66 therein.

67 designates a pipe secured at one end to the block 65 and communicating with the 90 chamber 66, the other end thereof being secured to the block 47 and communicating with the chamber 68 in said block.

69 designates a pipe having one end secured in the block 47 and communicating 95 with the chamber 68, the other end being connected with the block 65 and communicating with the chamber 70.

71 designates a pipe secured to the block 65 and communicating with the chamber 70, 100 the other end thereof being secured to the block 47 and having communication with the chamber 72, which leads to the air-outlet 73, the latter being in advance of the gas-outlet 58 in order that the heated gas coming from 105 the gas-outlet 58 into the chamber 74, surrounding the air-outlet 73, will be drawn into the chamber 75 by means of the heated air coming through the nozzle 73.

76 designates a casing which is in engagement with the chamber 75 and which is provided with the chamber 77, communicating therewith and also with the burner-tips 78.

79 designates mantle-supporting rods on which the mantles 80 are suitably secured.

81 designates the globe, which is suitably secured in a bracket 82, supported on a lug or extension 83, extending from the casing 76. A flange 84, fixed to the reflector 83, prevents the heat from escaping between the reflector and the globe.

The operation of the lamp will be readily apparent. Both the air-inlet and the gas-inlet may be controlled, as desired, so that the desired proportion of air and gas will be 125 employed. The gas entering through the pipe 3 will pass through the pipes 6, 9, and 11 and through the passages communicating therewith in the cap 4 and the bottom block 7 therin through the outlet 13 into the chamber 130.

ber 26 in a highly-heated condition and will be drawn into the chamber 27. The air coming from the pipe 17 will pass through the pipes 19, 21, and 23 and the chambers in the cap 4 and the block 7 through the discharge-nozzle 25 into the chamber 27. As both the air and the gas have been separately heated to a high degree, the gas will be oxidized in the chambers 27 and 28 and a gas produced which is a gas having a high percentage of oxygen. This gas produces an intense heat, and this heat coming in contact with the incandescent mantle produces a very intense and very brilliant light.

While in Fig. 1 we have shown the air as being connected with the atmosphere, in the embodiment shown in Fig. 2 we have shown a bellows actuated by a water-motor for producing the desired pressure or compression of the air, which enters the inlet-pipe 62 and passes through the pipes 64, 67, 79, and 71 and the chambers 63, 66, 68, 70, and 7, registering therewith, and through the nozzle 73 into the chamber 75. The gas entering in the pipe 45 will pass through the chamber 48 and pipes 49, 52, 54, and 56 and chambers 51, 53, 55, and 57 to the gas-outlet 58, thence into the chamber 74, surrounding the air-inlet 73, into the chambers 75 and 77, where the same action takes place as in the construction shown in Fig. 1 and the gas produced passes to the burner-tip 78 and the incandescent mantle 80 in the same manner.

It will be readily apparent that the proportion of heated air and heated gas which is admitted to the oxidizing-chamber may be regulated, as desired, by means of the valve in the air-inlet pipe and in the gas-inlet pipe and that also the pressure or compression of the air may be varied as desired, and that this may be done by any suitable means—such as a blower, fan, or other device—and still be within the scope of our invention.

It will also be apparent that while we have shown the separate heating-tubes as being parallel to each other and arranged either perpendicularly or horizontally the same may be arranged at any desired angle to each other or to the source of heat or spirally arranged, according to requirements.

A lamp of this character may be so constructed as to vaporize any volatile oil and this heated vapor carried through the tubes to the gas-outlet, where it will unite with the heated air entering the chamber in which the union takes place and form the gas in precisely the same manner as already described in the gas process.

We have found in practice that in a lighting device constructed in the novel manner herein described not only is produced a much more intense and brilliant light than the prior devices now in use, but also the consumption of gas in proportion to the amount of light produced is greatly decreased. By

separately superheating the gas and the air and then bringing these two gases together in the right proportion while in a highly-heated condition the gases oxidize, and the gas thus produced not only provides a more intense light and is more economical with the use of the gas, but the life of the incandescent mantle will be prolonged.

We are aware that it has heretofore been proposed to partially heat the gas and then mix the same with air in its normal condition, that it has been proposed to heat the air and mix it with gas in its normal condition, and that it has also been proposed to mix the air and gas in its normal state and then heat it; but in so far as we are aware we are the first in the art to separately heat the air and separately heat the gas and then bring the two products into a separate chamber, in which they may unite to form a gas which is a fixed product and which on cooling has substantially the same quality and efficiency as when in a heated condition, and our claims to these features are to be interpreted with corresponding scope.

It will be apparent that the heat given off by the lighting device has free access to the air-pipes and gas-pipes, so that the heat from the burners is employed to automatically superheat both the air and the gas, and the heated air and gas thus produced unite to form the gas which feeds the burners.

It will be apparent that the motor 59 may be any of the usual or conventional types of water or similar motors which are employed for creating moderate pressures at desired points, and as the same forms *per se* no part of our present invention we have deemed it unnecessary to describe the same in detail.

It will be evident that various changes may be made by those skilled in the art which will come within the scope of our invention, and we do not, therefore, desire to be limited in every instance to the exact construction herein shown and described.

Having thus described our invention, what we claim as new, and desire to secure by Letters Patent, is—

1. In a device of the character described, an air-chamber and a gas-chamber connected therewith, burners for superheating said chambers, a third chamber located between said burners and into which said air and gas chambers discharge and means for compressing the air supplied to said air-chamber.

2. In a device of the character described, a burner, a chamber connected therewith, separate air and gas chambers discharging into said first-named chamber and heated by said burner and means for controlling the flow of air and gas to said air and gas chambers.

3. A gas-burner having in combination, separate air and gas chambers, means for separately heating said chambers, a chamber

connected with said air and gas chambers and means for leading the gas formed in said last-named chamber to the point of utilization.

5 4. In a burner, an air-chamber adapted to be heated and having a discharge-port, a separate chamber into which said port discharges, a gas-chamber adapted to be heated and having a discharge-port in proximity to said air-port and in communication with said separate chamber.

5 5. In a burner, a chamber, separate air and gas chambers discharging therein, a burner-tip in communication with said first-named chamber, a mantle supported above said tip, and said air and gas chambers being located adjacent to and superheated by the heat from said mantle.

6. The combination of an air-conduit and 20 a gas-conduit, separate and independent air and gas chambers into which said conduits lead, a third chamber, conduits leading thereto from the air and gas chambers, and means for heating all of said chambers whereby the 25 air and gas supplies are independently pre-heated before conduction to said third chamber.

7. In a lamp, an air-chamber, a gas-chamber, means for heating said chambers, a third chamber into which the heated air and gas 30 discharge, a casing surrounding said air and gas chambers and means for permitting the admission of heated air thereto and its escape therefrom.

8. In a lamp, a plurality of burners, mantles therefor, a chamber leading downwardly between said mantles to a lower chamber, an inlet-pipe for air, a heater therefor consisting of a plurality of pipes arranged above one of said burners and discharging the heated air 40 into said first-named chamber; a gas-inlet, a plurality of gas-pipes arranged above one of said burners and discharging into said first-named chamber in combination with a nozzle leading from said air-heater and serving 45 to accelerate the discharge of air and gas into said first-named chamber and means for conducting additional air-pressure to said air-heater.
